DESIGN FOR A BOTTLE

Bert F. Strand, Jr., Toledo, Ohio, and Walter Henry Meyer, Erie, Mich., assignors to Krim Beverage Company, Lebanon, Pa., a partnership consisting of Max Krim, Irwin Krim, and Nathan B. Krim

Application October 24, 1939, Serial No. 87,838

Term of patent 14 years

To all whom it may concern:

Be it known that we, Bert F. Strand, Jr., a citizen of the United States, residing at Toledo, county of Lucas, and State of Ohio, and Walter Henry Meyer, a citizen of the United States, residing at Erie, county of Monroe, and State of Michigan, have invented a new, original, and ornamental Design for a Bottle, of which the following is a specification, reference being had to the accompanying drawing, forming a part thereof.

In the drawing:

We claim:

The ornamental design for a bottle, substantially as shown.

BERT F. STRAND, JR.
WALTER HENRY MEYER.
